UNITED STATES PATENT OFFICE.

OWEN SHEEHAN, OF NEW BEDFORD, MASSACHUSETTS.

WARPING-MACHINE.

SPECIFICATION forming part of Letters Patent No. 322,014, dated July 14, 1885.

Application filed December 29, 1883. (Model.)

To all whom it may concern:

Be it known that I, OWEN SHEEHAN, a citizen of the United States of America, residing at New Bedford, in the county of Bristol and State of Massachusetts, have invented certain new and useful Improvements in Warping-Machines, of which the following is a specification, reference being had therein to the accompanying drawings.

10 This invention relates to machines for reeling yarn; and it consists of the sundry combinations and arrangements of parts substantially as hereinafter fully set forth and claimed, whereby the shifting or movement of the several parts of the machine and the reversal of the rotation of the reel is effected automatically.

15 In the accompanying drawings, Figure 1 is a rear elevation of my machine. Fig. 2 is a plan view thereof. Figs. 3 and 4 are different end views. Fig. 5 is a sectional elevation on the line $x-x$, Fig. 2. Fig. 6 is a cross-sectional elevation on line $y-y$, Fig. 2. Fig. 7 is a horizontal section taken below the reel.

20 Fig. 8 is a transverse section, looking toward the driving end of the machine on the line $z-z$, Fig. 2. Fig. 9 is an enlarged detail view of the carrier-carriage L. Fig. 10 is a similar view of the carriage-supporting frame m^2 , and Figs. 11 and 12 are views of the pulleys and their straps with the inner flange edge of each pulley removed.

25 In carrying out my invention I construct a suitable frame, A, such as will be conveniently adapted for supporting the operative mechanism.

30 B is the reel, with its shaft a , which is suitably journaled upon the frame A, provided at the driving end with a gear-wheel, a^4 , gearing with a small pinion, a^2 , located on the same stud a^3 with the gear-wheel a^4 , to which it is rigidly connected, said stud being rigidly secured to a cross-piece of the frame A by ordinary means. The gear-wheel a^4 gears with a small pinion, a^6 , secured to a shaft, a^6 , which latter is journaled at its ends upon cross-pieces of an annex of frame A, and carries two loose pulleys, b b , and a fast pulley, b' , arranged centrally or between the loose pulleys.

35 C are the driving-drums, which are located immediately beneath the aforesaid pul-

leys, their shaft being suitably journaled in castings or supports secured to lower cross-pieces of the annex of frame A.

55

D D' are two belts, so applied to the driving-drums and the fixed pulley b' that while one is on the fixed pulley the other is on the loose pulley, and reversely, one being a straight belt and the other being a crossed belt, from 60 which source, through the above-described train of gearing, the reel is driven first in one direction and then the other, as will appear further on.

Upon the opposite end of the reel-shaft a , 65 or rather a short distance inward therefrom, is a small pinion, c , meshing with two gear-wheels, D^2 D^2 , mounted and free to revolve on studs rigid with or fixed in brackets d d , secured to the side of a cross-piece of frame 70 A. These gear-wheels D^2 D^2 are provided on one side with small grooved drums or windlasses D^3 D^3 , which are formed or cast therewith, and sleeved upon their shafts, to turn with said wheels, which will be further referred to hereinafter.

75 Hung or pivoted upon brackets e , fastened to uprights of the frame A, a short distance below and about in the same vertical plane with the reel-shaft a , are pulleys E E', to the inner sides of which are fastened projecting arms E^2 E^3 , which are curved upwardly in reverse directions and arranged in the plane of rotation or path of two arms or projections, f' f^2 , constituted, respectively, by projecting 80 a short distance outwardly from the disks or bands of the reel the opposite ends of two peripheral bars, f f^3 , of the reel B, which will be explained further.

85 Attached to the pulley E are short straps F 90 F' F^2 F^3 , (see Figs. 6 and 12,) which are secured at one end by ordinary means to the said pulley at the point F' , and to the other or free end of the strap F is connected a cord or line, G' , passing over a pulley, g' , depending 95 from the frame A some distance forward of the point of connection of the said cord or line to the strap, and thence over a second pulley, g , depending from the frame A a short distance rearward from the pulley g' , whence it is connected to one, J, of two hammer bars or levers, J J' , presently described. The second cord or line, G , connected to the aforesaid strap F' , is passed over a pulley, k , whose

block or support is fastened to the inner side of one of the uprights of the frame A, and thence connected to the lower end of one, I, of two levers, I I', pivoted in the upper front bar, I², of the frame in the path or plane of travel of the carriage, hereinafter described, the normal position and operation of which levers are just the opposite of that of the hammer bars or levers J J'. The hammer bars or levers J J' are pivoted near their lower ends to the same side of said front bar of frame, and connected together at their extreme lower ends by a spring, I³, the action of which is to deflect outwardly the upper ends of said hammer-bars, or cause their said latter ends to be removed farther apart. The levers I I' will be treated of further on. Another cord or line, G¹¹, which is connected to the short strap F¹⁰ of the pulley E, passes down around a pulley, g², whose support is fastened to a central bottom piece of the frame A, and from there around a pulley, g³, similarly connected to the other end of said bottom piece. From here it passes upward around another pulley, g⁴, Fig. 8, likewise connected to an upright of the frame A, and again around another pulley, g⁵, Fig. 2, whose support is connected to the annex of the frame A, and thence extended and fastened to the belt-shipper H. Said belt-shipper is fulcrumed upon a bracket fastened to said annex of the frame A, and provided at one end with a hook, H', which embraces one side of and controls the shipping of one driving-belt, while at a short distance inward from the hook H' said shipper is provided with a second hook, H², which embraces one side of and controls the shipping of the crossed belt. The pulley E is controlled by a spring, i, fastened to one of the lower horizontal cross-pieces of the frame A, said spring being also connected by a cord, i', to the short strap F⁸ of the pulley E.

Attached to the pulley E' are short straps F² F³ F⁴ F⁵, (see Figs. 8 and 11,) which are secured at one end by ordinary means to the said pulley at the point F⁵, and to the other or free end of the strap F² is connected a cord or line, G², passing around a pulley, j, whose support is fastened to the inner side of one of the uprights of the frame A at that end thereof, and it is then connected to the lower end of the lever I'. A cord or line, G³, is connected to the outer or free end of the strap F³, and is passed first over a pulley, m', and under a pulley, m, whose blocks or supports are suitably fastened, one to a side bar of the frame A, and the other to the inner side of the front bar. Said cord or line is then connected to the lower end of the hammer bar or lever J'. The strap F⁴, likewise secured to the pulley E' at the point F⁵, as before stated, extends upward a short distance, and to the end of said strap F⁴ is connected another cord or line, G⁴, which is carried upward and over a pulley, l, at the uppermost end of the frame A, and thence downward and passed around under a pulley, g⁶,

supported upon the annex of frame A, and thence connected to the belt-shipper H. The pulley E' is controlled by a spring, i², similar to that which controls the pulley E. Said spring is likewise fastened to one of the lower horizontal cross-pieces of the frame A, and is also connected by a cord or line, i³, to a short strap, F⁹, of the pulley E'. 75

K is a sliding check-rod which passes through and rests in tubular brackets m'', fastened to the inner sides of the front corner-posts of the frame A, and through a similar bracket, m⁴, fastened to a frame, m², secured 80 around the carriage L, whose lower end is fitted to travel in a groove of the upper front bar, I², of the frame A, said frame m² (containing the carriage) being provided with eyes for reception of and to permit of its sliding upon a rod, M, secured in the upper ends of the front corner-posts of frame A. 85

Hung in the upper and lower portions of an opening of the carriage L are grooved rolls n, between which the yarn passes to the 90 reel B.

To revert to the check-rod K, it will be seen that it is controlled by two cords or lines, N N', connected indirectly to the belt-shipper H, as will appear hereinafter. The cord or line N is connected to an eye, N⁶, fastened to said rod, and thence passed over a pulley, o, whose bracket or block is fastened to the inner side of one of the front corner-posts of frame A, whence it is passed around two 10 pulleys, o' o', Fig. 3, thence carried upward and over a pulley, o², at the uppermost end of said frame, and finally carried across the frame to and around a pulley, o³, at the opposite side of the frame, where it is connected 105 with or to the cord or line G⁴ of the pulley E', connecting with the belt-lever H. The cord or line N' is likewise connected to an eye, N⁷, fastened to the check-rod K, and is passed over a pulley, o⁵, upward to and over a pulley, o⁴, upon the frame A directly under the pulley o³, whence it is passed down and connected with or to the cord or line G¹¹ just before the latter is passed over the pulley g⁵, leading to and connected with the belt-shipper H, as before stated. By this arrangement it will be seen that the two lines, N N', (one moving with the sliding check-rod K to the right and the other moving with said rod to the left,) are connected, one, N, to the cord 120 or line G⁴, leading from the pulley E, and the other, N', to the cord or line G¹¹, leading from the pulley E', the purpose of which will appear further on. 115

O⁶ is a cord or line connected to or passed 125 through an eye or tubular extension, O⁷, on the carriage-frame m², and knotted on each side of said eye. The cord or line O⁶ is passed around a pulley, p, connected to one of the front corner-posts of the frame A. Said cord or line is then connected to and coiled around the grooved drums or windlasses D³ D² of the gear-wheels D², said line being passed to said windlasses from the upper side, and after hav- 130

ing been coiled around said windlasses a suitable number of times it is then passed around two other pulleys, $p' p'$, arranged upon the upper rear bar of the frame near its rear corner-posts, after which it is extended to and passed around the pulley p^2 , connected to one of the front corner-posts of the frame A, and is then connected to or passed through an eye or tubular extension, O^8 , on the carriage-frame m^2 , (knotted on each side of said eye,) the effect of which arrangement is to enable the moving of the carriage L in either of two directions—to the right or to the left—as will be more fully understood hereinafter.

15 P is the guide through which the yarn is fed, after the passage of the latter through the opening, and between the rolls of the carriage to the reel B, said guide having a straight central portion provided on its upper side at the rear end with an eye for the passage of the yarn, and having two curved forwardly-projecting arms, $P' P^2$, extending to each side of the carriage L, and transversely to its line of travel. The guide P is pivoted by one of said arms, P' , to one of two parallel arms, $q' q'$, in turn pivoted to vibrate vertically upon the carriage L, while its other arm, P^2 , is provided on the under side with a projection or stud, r , entering a slightly curved slot, s , in the arms q' , whereby the guide is allowed to adapt itself to the direction in which the yarn is being fed upon the reel, which is controlled according to the direction of its rotation, and to have a horizontal back-and-forth movement upon its pivot to shift the direction of feeding the yarn upon the reel.

30 $Q Q'$ are two hooks, clamped adjustably upon longitudinally-slotted plates or bars, $Q^2 Q^3$, which are sleeved and capable of sliding or 40 adjustment upon peripheral rods of the reel B, one hook pointing forwardly and the other rearwardly.

In operation it will be seen that presuming the reel B to be in action, laying the yarn 45 thereon, and the carriage L to have traveled to or as far as the lever I, which movement of the carriage is effected by the cord or line O^6 , (connected to the eyes O^7 and O^8), drums D^3 50 and gearing $D^2 D^4$, the belt-shipper cord or line N , connected to an eye, N' , of the check-rod K, will be so acted upon by the said check-rod K as to cause, in connection with the cord or line G^1 , to which it is connected, the shipper H to ship the belt D from the fast pulley 55 b' upon one of the loose pulleys b , and thus ship the belt D' upon said fast pulley b , thereby causing the reversal of the operative mechanism by the reversal of the transmittal of power. When the carriage L traveled as far 60 as and operated the lever I, as before stated, the cord or line G , connected to the pulley E, in causing the partial rotation of said pulley thereby brought its arm of projection E^2 in plane to be acted upon by the projection f' of 65 the reel-arm f , thereby stopping the direction of the rotation of said reel, as also causing the shipping of the two driving-belts, whereby the

reversal of the operative mechanism was effected, as before stated. Immediately upon release of the projection f' of the reel-arm f from the arm or projection E^2 the pulley E is returned to its normal position by action of the spring i . The reversal of the rotation of the reel having been effected, as above stated, the same will continue to revolve, and consequently 70 continue to act upon the carriage L until the same acts upon the contiguous lever I', which will, through the cord or line G^2 , act upon the pulley E', which will thus receive a partial rotation and bring its arm or projection E^3 in 75 plane to be acted upon by the projection f^2 of the reel-arm f^2 , and effect the stopping of the direction of the rotation of the reel and the shifting of the driving-belt, which latter is effected by the cord or line N' connected to 80 the check-rod K in conjunction with the cord or line G^4 of the pulley E'. By this movement the belt-shipper H is caused to ship belt D' from the fast pulley b' to one of the loose pulleys b , and thereby ship the belt D upon said 85 fast pulley, and thus again causing the reversal of the transmittal of power, and cause the reel to revolve in the required or reverse direction from that in which it last revolved, to effect the reverse laying or winding of the 90 yarn thereon. Simultaneously with the action of the carriage L on the lever I' the partial rotation imparted to the said pulley E' will pull upon the hammer-bar or lever J' through the cord or line G^3 , and cause said rod or lever 95 to strike the guide P, which will effect the throwing or looping of the yarn carried thereby over a hook or projection, Q' , of the plate or bar Q^3 , the same being the oppositely-projecting hook from that around which the yarn 100 was previously looped, which was effected by the corresponding means. In again reversing the motion of the reel it will be understood that the duplicate mechanism of that referred to in connection with the operation as just 105 detailed will be brought into requisition, effecting the reversal of the travel of the yarn-guide, together with its aforesaid adjunctive parts and the consequent laying of the yarn in a reverse direction upon the reel.

Having thus fully described my invention, what I claim, and desire to secure by Letters Patent, is—

1. The combination, with the driving-pulley, belts, gearing mechanism, and belt-shipper, of the reel having end projecting arms, the pulleys having the arms or projections, and levers connected to said pulleys, the lines connecting said pulleys to the belt-shipper, of the cords or lines of the sliding check-rod, 115 substantially as and for the purpose set forth.

2. The combination, with the reel having projecting end arms and its shaft, gearing driving the latter and gearing driven thereby, and windlasses or drums affixed to said latter 120 gearing, of the guide-carriage, the guide connected to arms of the latter, the line connecting the guide-carriage to the windlasses, the pulleys, the hammer-bars or levers, the

lines connecting the said hammer bars or levers to said pulleys, and the levers disposed in the line of travel of the carriage and connected to said pulleys, substantially as and for the purpose set forth.

3. The combination, with the reel having peripheral hooks and projecting end arms and its shaft, the gearing driving said shaft and the gearing driven thereby with driving-belts, windlasses or drums affixed to the latter gearing and the belt-shipper, of the horizontally and vertically movable guide-carriage, the guide connected to arms of the latter, the lines connecting the carriage to the windlasses, the pulleys, the lines connecting the latter to the belt-shipper, the hammer bars or levers, the lines connecting said hammer bars or levers to said pulleys, the guide-arresting levers, and the lines connecting said levers to said pulleys, substantially as and for the purpose set forth.

4. The combination, with the reel having peripheral hooks and projecting end arms and its shaft, the gearing driven by said shaft with driving-belts, windlasses or drums affixed to the latter gearing and the belt-shipper, of the guide-carriage, the guide connected to arms of said carriage, the lines connecting the said carriage to the windlasses, the pulleys, the lines connecting the pulleys to the belt-shipper, the pivoted hammer bars or levers, the lines connecting said hammer bars or levers to said pulleys, the guide-carriage arresting-levers, the lines connecting said levers to said pulleys, the check-rod, and the lines con-

necting the latter to the belt-shipper lines, substantially as and for the purpose set forth.

5. The combination, with the reel having peripheral hooks and projecting end arms and its shaft, the gearing driving said shaft, the 40 gearing driven by said shaft, with driving-belts, and windlasses or drums affixed to the latter gearing, of the guide-carriage, the guide connected to arms of said carriage, the line connecting said carriage to the windlasses, the 45 pulleys, the springs, the lines connecting said springs to said pulleys, the lines connecting said pulleys to the belt-shipper, the spring for connecting the hammer bars or levers, the lines connecting said bars or levers to 50 said pulleys, the guide-carriage arresting-levers, the lines connecting said levers to said pulleys, the check-rod, and the lines connecting said latter rod to the belt-shipper lines, substantially as and for the purpose set forth. 55

6. The combination, with the reel having peripheral oppositely-projecting hooks secured to the slotted plates or bars attached to the reel, of the guide pivotally connected to arms of the guide-carriage, the hammer bars 60 or levers, and the lines connecting said bars or levers to the pulleys, substantially as shown, and for the purpose set forth.

In testimony whereof I affix my signature in presence of two witnesses.

OWEN SHEEHAN.
